STRUCTURE

Frederick H. Ruppel, Pasadena, Calif.

Application December 10, 1932, Serial No. 646,579

10 Claims. (Cl. 189—1)

My invention relates to a frame structure suitable for buildings, the invention being especially suitable for smaller types of buildings, such as one and two story residences and light commercial structures.

Since my invention is especially suited for residence construction, and since the principles of the invention remain unchanged in their use in various types of structures, the following disclosure will be limited to the embodiment of the application of the invention in a residence structure.

In residence and light commercial construction, steel is usually supplementary to the other materials used, and in many instances the use of steel structural members is entirely avoided. For example, the main walls of light structures of this character may be constructed from brick, tile building blocks, or wood, with the inner dividing walls formed either of tile or wood and plaster, with wood finish applied thereto. In such structures steel may be at times employed as lintels or girders, but this use of structural steel members does not add to the strength or permanence of the main structure but is merely for the purpose of carrying a load in some part of the structure. Steel, however, has not been extensively employed in small buildings in the same manner as it has been employed in large structures, such as office buildings, auditoriums, etc. In such large structures the structural steel members are joined together to form a complete frame structure, reinforced and braced so as to carry the entire weight of the structure. Masonry tile and facing and finishing materials are attached to or supported by the fabricated steel frame structure. Contrary to this, small structures, as a general rule, do not have the structural steel members used therein tied into the frame of the building in the manner in which structural steel is employed in large buildings. I am aware, however, that some development work has been done on light steel frame structures for smaller types of buildings, using steel pipe as the structural members or employing other light steel shapes. But it is found that the means and method of steel construction for small building which have been developed have not found extensive use, especially in residence construction where wood seems to be adopted owing to the relative ease with which it may be cut to desired length and these lengths secured together by nails or spikes.

It is an object of my invention to provide a simple frame structure and means for produc-

ing such a frame structure from metal such as steel, such structure, due to its simplicity and the ease of erection of the parts thereof, being comparable in cost with the other types of construction, such as wood or masonry.

An especial feature of the invention is that it enables the production of a steel frame structure for a light building at a cost competitive with the making of the structure entirely from wood or masonry or a combination of wood and masonry, but greatly superior to either of these forms of construction owing to the permanence of steel, its greater resistance to destruction by earthquakes or by fire, low cost of maintenance, and freedom from termite, rot, and fungus attack. Those who have had occasion to dismantle wood structures of an age of ten years or more are strongly impressed by the lack of permanence and the very pronounced diminution in the physical strength of such structures due to the unsatisfactory means whereby they are secured together, namely, nails and spikes, which rust or corrode in the presence of moisture and organic chemicals in the wood.

It is an object of my invention to provide a steel frame structure fabricated from tubular sections such as pipes by use of fittings of novel form which may be applied without the necessity of severing the pipe members to which they are attached, thereby preserving greater strength in the structure than where the various pipe members are assembled by screwing them together with known types of threaded pipe fittings. My invention makes possible the economical employment of what is known as a balloon type structure in which the vertical pipes, such as posts or studs, extend continuously from the foundation to the roof or attic without being cut at intermediate points for the insertion of fittings for the attachment of laterals or reinforcing members.

It is an object of my invention to provide a structural member comprising a metal tube having lateral external grooves on intermediate portions thereof whereby fittings for connecting members may be attached without necessity of severing the structural member.

A further object of the invention is to provide fittings for securing together tubular structural members without the necessity of severing the tubular structural members at intermediate points, such fittings having projecting keys or ribs for engaging grooves or ribs formed on the tubular structural members, so that movement of the fittings on the tubular structural members, under pressure of a load applied thereto, cannot

take place and so that in the connection of the fittings to the tubular members the full strength of the fittings and of the tubular members is developed. It is known that saddle clamps are employed for securing to pipes other pipes or members, but these saddle clamps are not suitable for structural work of the class to which the present invention relates, since such saddle clamps depend upon frictional engagement with the pipes to retain them immovable, and even where large bolts are employed to bolt up the saddle clamps so as to withstand a given load, rust or loosening of the bolts will destroy the frictional engagement and permit the saddle clamps to move under the load which they are intended to transmit to the pipe.

It is an object of the invention to provide a fitting of the above character comprising cooperating hinged parts adapted to be bolted or pinned around a pipe member, the inner faces of such cooperating clamps having laterally or circumferentially extending rib or groove means therein for interlocking engagement with similar rib or groove means formed upon the pipe to which the fitting is secured.

A further object of the invention is to provide a building frame comprised of hollow posts and laterals constructed of pipe secured together by fittings of such character that there is no communication between the interiors of the posts and laterals, and vice versa, thereby enabling selected pipes, such as the posts, to be used as conduits for electric wiring or for fluids. By use of the invention, conduits, water-pipes, and drain-pipes become a physical part of the structure instead of being hung therein as in common practice.

Further objects and advantages of the invention will be made evident throughout the following part of the specification.

Referring to the drawings, which are for illustrative purposes only,

Fig. 1 is a fragmentary perspective view showing my invention embodied in a balloon type frame structure for a building.

Fig. 2 is an enlarged fragmentary cross section on a plane represented by the line 2—2 of Fig. 1.

Fig. 3 is a fragmentary cross section taken as indicated by the line 3—3 of Fig. 2.

Fig. 4 is an enlarged view showing a form of my new structural fitting with the parts thereof swung into open position.

Fig. 5 is a partly sectioned perspective view of a form of my fitting adapted to secure lateral members on diametrically opposite sides of a beam, stud, or post member.

Fig. 6 is a perspective view showing the fitting adapted to connect to a post or column lateral members which extend at right angles to each other and at right angles to the post.

Fig. 7 shows a form of my new structural fitting adapted for the attachment of reinforcing cables.

Fig. 8 is a vertically sectioned view showing the manner in which floor and wall members may be secured to a frame structure of the character shown in Fig. 1.

Fig. 9 is a fragmentary cross section on a plane represented by the line 9—9 of Fig. 8.

Fig. 10 is a fragmentary elevational view showing how my invention lends itself to the forming of trusses or diagonal bracing.

Fig. 11 is a perspective view of the adjustable attachment means shown in Fig. 10.

In the form of my invention shown in Fig. 1,

a frame structure 12 for a residence building is fabricated from pipes such as 13, 14, and 15. An especial feature of the construction shown is that the posts 13 and the studs 14 may be each carried in one continuous length from a foundation 16 preferably of concrete to the horizontal capital members 15, the intermediate lateral pipes, such as the members 17 and 18, all being secured in place by use of fittings which are attached to the pipes 13 and 14 without the necessity of cutting such members 13 and 14 in order to provide threaded ends to be screwed into the fittings at the ends of the members 17 and 18. As an example of my new construction, the front post 13 is shown in Figs. 2 and 3 supporting a right angle fitting 20 of the character shown in Figs. 4 and 6 in a position intermediate the ends of the member 13 and for supporting horizontal pipes 22 and 23 serving as girts for supporting plates 24, which may be of wood, and the second story floor joists 25, the ends of which rest upon the plates 24. As will be especially noted in Fig. 3, the intermediate portion 26 of the corner post 13 has lateral grooves 27 formed in the external face thereof. In the preferred practice of the invention the grooves 27 extend entirely around the pipe 13 and may be either circular or helical. As best shown in Figs. 2 and 4, the fitting 20 is comprised of cooperating semi-cylindrical wall members 30 and 31 having ribs 32 on the inner faces thereof adapted to extend into the grooves 27 of the pipe 13 when the fitting 20 is in place on the pipe 13 as shown in Figs. 2, 3, and 6. As shown in Fig. 4, the wall members 30 and 31 have hinge lugs 33 and 34 through which a pin 35 is extended to furnish hinge means 36 for swingably securing the members 30 and 31 together. Being hinged together in the manner shown, the parts 30 and 31 may be swung into relatively open position as shown in Fig. 4 and may be closed around the grooved portion 26 of a structural member such as the pipe 13 and there clamped in operative position by use of lugs 37 projecting from the sides of the members 30 and 31 opposite to the hinge 36 and having openings 38 therein through which a bolt 39 may be extended. In Fig. 6 I show the fitting 20 with two hinge structures 36 each of which may have removable tapered hinge pins 36', the placement of which will cause the parts 30 and 31 to be drawn tightly together around the grooved portion of the pipe 13. This form of the invention is especially suitable for heavy service owing to the great strength of the hinge means 36.

For securing the ends of the horizontal pipe members 22 and 23 to the fitting 20, I provide socket members 41 which, as best shown in Fig. 6, preferably consist of channel-shaped or substantially semi-cylindrical walls 42 extending outwardly from one of the walls of the fitting 20, such as the member 30 thereof. The fitting 20 is preferably placed with the socket members 41 facing upwardly so that the ends of the horizontal pipe members 22 and 23 may be rested thereon prior to the securing of the ends by passing bolts 43 through openings 44 in the side walls of the socket members 41 and through openings in the ends of the pipes 22 and 23, which openings are preferably spot-drilled from the openings 44 while the ends of the pipes 22 and 23 rest in the sockets 41. As shown in Figs. 2 and 3, the sockets 41 may be provided with ribs 41', and the ends of the pipes, such as the pipe 22, may be provided with grooves 22' to engage the ribs 41'.

to supplement the bolts 43 in bonding the pipe ends to the fittings.

From the foregoing description it will be noted that the fitting 20 is secured to the pipe 13 without severing the pipe 13. As shown in Fig. 1, fittings 20a, of the same character as the fitting 20, and other fittings 20b are secured upon the post 13 between the foundation plate 45 and the extreme upper end of the member 13. Since these fittings are all of the split character previously disclosed and are mounted upon the grooved portion of the pipe 13, such pipe is permitted to extend continuously from the foundation 16 to the roof plane of the structure without interruption and without internal connection with the pipes connected thereto by the fittings.

In this simple method of construction the entire corner post of the building frame is placed in a single piece, instead of in small sections 20 threaded into the various fittings disposed throughout its length, and the fittings 20, 20a, and 20b disposed along the length of the pipe 13 may be secured in place and have the interconnecting lateral pipes secured thereto in much less time than the fabrication of the same structure by use of pipes which thread into pipe fittings of standard type. In this method of construction, the formation of grooves with intervening ribs on an intermediate portion of the pipe 13 provides a plurality of horizontal shoulders adapted to be engaged by horizontal shoulders formed on the inner faces 30 and 31 of the fitting 20, and through which shoulders the load carried by the fitting 20 is positively transmitted to the pipe or column 13, all of which is accomplished without the necessity of cutting through the pipe or severing the pipe to insert a threaded fitting.

The second floor 46 shown in Figs. 1 and 3 is carried on the floor joists 25, some of which floor joists 25 transmit their load to the pipe 22 of Figs. 1 and 3 and similar pipes 22a shown only in Fig. 1. Accordingly, a portion of the load of the floor 46 must be carried by the fitting 20, and it is therefore imperative that a positive bond be formed between the fitting 20 and the pipe 13 so that there will be no possibility of the fitting moving downwardly on the pipe 13 in response to the application of the floor load thereto. This desired result I have very satisfactorily accomplished in the provision of a main structural member, such as the post 13, having externally grooved portions intermediate the ends thereof, and separable fittings adapted to be clamped against or around such grooved portions, these fittings having ribs for cooperative interengagement with the grooves. It is preferable that each grooved section of the pipe be a little longer than the ribbed portion of the fitting to be applied thereto so that such fitting may be adjusted longitudinally upon the grooved portion.

Previously herein I have described a form of fitting 20 adapted for a particular utility in a frame structure. Such fitting may be varied in design to meet the various requirements of a frame structure without abandoning the valuable features thereof. For example, the bearing plate 45, shown in Fig. 1 and further shown in Fig. 8, is made in two cooperating semi-cylindrical segments 47 adapted to be clamped together around a grooved portion 48 of a post or stud, such as the pipe 13 of Fig. 1 or the pipe 50 of Fig. 8.

The load carried by the vertical pipe member

is accordingly positively transmitted to the bearing plate 45 and is thereby transmitted to the foundation member 16 or 16a. As further shown in Fig. 8, it is preferable to extend the lower end 51 of a vertical post or stud down into the body of concrete 52 constituting the foundation member, thereby firmly tying the posts to the foundation so that the stability and bonding of the foundation with the ground resist overturning movement of the vertical pipe members 10 embedded therein.

The fitting 53 shown in Fig. 5 comprises cooperating parts 54 adapted to be clamped around a grooved portion 55 of a stud 14 or to the pipe member 56, and having diametrically extending connection sockets 57 formed thereon, such fitting 53 being adapted, as shown in Fig. 1, to secure to an intermediate portion of a stud 14 or other member in the structure lateral pipes 18 which extend at right angles to the member 14. 20 Where a lateral pipe 56, as shown in Fig. 1, is to be secured between vertical pipes 58 and 59 for the purpose of reinforcement or for outlining a window opening, a fitting 60 may be employed which is identical with the fitting 53 with the exception that, as shown in Figs. 1 and 10, it employs only one laterally projecting connection socket 57.

From the foregoing, it will be perceived that the fittings may be provided with sockets extending either perpendicularly or in any other desired direction. For example, in Fig. 3 a fitting 62 is shown on a grooved portion 63 of the pipe 13 above the fitting 20, this fitting 62 having a diagonally extending socket 64 for securing to 30 the member 13 the lower end 65 of a diagonal pipe 66 serving as a reinforcing strut. Fittings 62 for diagonal connection of pipe members are preferably made with the pipe receiving sockets 64 thereof disposed at angles of thirty, forty-five, 40 and sixty degrees, thereby making it possible with three types of diagonal fittings to accommodate the various conditions which may be encountered in the erection of a structure.

It is a further object of the invention to provide a steel frame structure reinforced by diagonal cables, and in Fig. 7 I show a fitting 70 preferably comprising hinged parts 71 having interior ribs for engaging the grooved portions 72 of a pipe 73 and having projecting webs 74 50 equipped with openings 75. To these openings 75 diagonally disposed reinforcing cables are attached, in the manner of the cable 76 of Fig. 7. In this manner a simple and economical diagonal reinforcing means for a building structure 55 may be provided. Cables are subject to elongation due to stretching after they have been placed, but turnbuckles may be employed therein for varying the tension in the cables.

As an adaptation of another form of my fitting, Figs. 1, 2, and 3 show split fittings 80 having flat walls or pads 81 formed thereon, across which pads the wooden plates 24 for supporting the ends of the floor joists 25 may be extended. The pad 81 may be provided with threaded openings 82 to receive screws or bolts for attaching the plate 24 thereto, the ends of the joists 25 being thereafter secured to the plate 24 by use of nails or bolted angle clips in accordance with construction practices.

Where floors, balconies, or other elements of a building are unsupported by intermediate posts or columns, my invention readily adapts itself to the economical formation of girders or trusses. For example, in Fig. 1 a concrete floor 84 is shown 75

with its peripheral portions supported on diagonally reinforced lateral pipe members 85 carried by the vertical posts and studs of the structure 12. The intermediate portions of the concrete floor 84 may be carried by a truss 86 readily fabricated from pipe members. The upper and lower horizontal pipes 87 and 88 of the truss 86 may be unbroken throughout their entire length, and the diagonal pipes 89 of the truss 86 may be secured thereto by use of surrounding fittings of the general character previously described. Over large doorways 101 lintels 102 of truss form may be employed in the general form shown in Fig. 1 using structural fittings of the character previously described herein.

My new form of fitting may also include screw-threaded socket members for receiving the ends of pipes, and for the purpose of illustration I have in Fig. 10 shown fittings 110 of this character secured to a vertical pipe 111 and to a lateral pipe 112. Such fitting 110 includes cooperating semi-cylindrical parts 113 and 114 having internal ribs and being adapted to be clamped by pins or bolts 115 on a grooved portion 116 of a pipe, such as the pipe 111. From the part 113 of the fitting 110 a web 117 extends having openings 118 therein through which bolts 120 may be extended for the purpose of securing socket members 121, of the character illustrated in Fig. 11, to the main body of the fitting 110. Such socket members 121 may be cut from heavy-walled pipe or tubing so as to form a cylindrical portion 122 having a pair of spaced legs 123 adapted to extend on opposite sides of the web 117, and having openings 124 through which a bolt 120 may be passed. As shown in Fig. 10, these socket members are internally threaded so as to be screwed upon the ends of interconnecting pipe members, such as struts 125. It is also a feature of the invention to provide the socket members 121 with right-hand and left-hand threads so that the ends of a strut may be provided with right-hand threads 126 and left-hand threads 127 to enable the adjustment of the strut relative to the sockets 121 by rotating the pipe 125. Accordingly, if this form of fitting is employed in a truss or for diagonal reinforcing purposes, the effective length thereof may be increased or decreased by rotating the strut or reinforcing member so as to bring the interconnecting parts of the structure into desired relation in order that the cooperating parts of the structure will each sustain the proper portion of the load carried by the structure.

A truss of the character shown in Fig. 10 may be readily designed and assembled at the structure. The grooved portions 116 and 128 of the pipes employed may be readily formed by use of either a hand-operated or power-operated external grooving tool. The socket members 121, being pivotally connected to the webs 117, may be disposed at any desired angle; therefore, accurate computation of the length of the struts and chords of the truss is not essential. The horizontal or lateral member 112 and the lower chord member 130 of the truss may extend continuously from one end of the truss to the other. The pipe member 130 is shown connected to a socket 121a by use of screw-threads 131 which may be made right-hand and left-hand at opposite ends of the pipe so that the effective length of the chord may be adjusted by rotation of the pipe 130 after assembly of the parts of the truss.

A feature of my invention is to fill selected horizontal or vertical pipe members, such as the

pipe 22 of Fig. 6 or the post 13 of Fig. 3, with a core which may consist of concrete grout 135 so as to develop from pipe members structural beams and columns of great strength and stiffness, thereby minimizing deflection.

A further feature of my invention is that it provides for considerable flexibility of design. In the ordinary types of steel construction for light buildings, the manufacturing equipment, such as stamps and dies, etc., are made for certain fixed designs. To vary from these standard designs is relatively expensive, but in my new construction the structural parts are of such character that they may be assembled to correspond to any desired design, and changes in design of a structure do not require changes in the manufacturing equipment, for the reason that the interconnecting fittings are of standard form and the pipe members may be grooved at desired points to receive the pipe fittings in accordance with the requirements of the design. Furthermore, many of the structural parts may be cut to length and grooved where desired on the job, and in fact all of the pipe members for a frame structure may be prepared on location from plans. Furthermore, my simple construction enables the changing of the frame structure to suit changes in design which may be made after the frame structure is fully or partly completed.

A steel frame structure of the character shown in Fig. 1 may be employed to support any desired finish, such as wood, stucco, tile, or brick, such finish being secured to the steel structural members by use of commonly accepted methods. For example, in Fig. 8 I show a stud 50 of a building frame to which an outer stucco wall surfacing 140 and an inner plaster finish 141 are applied. For securing the walls 140 and 141, furring strips 142 may be secured to the pipe members of the structure in any desired manner. In Fig. 9 the pipe 50 is shown with openings 143 therein to receive attachment members 144 for securing the furring strips 142 in place. As shown at 144a in Fig. 9, the attachment means 144 comprises a metal strip 145 bent to form a pair of legs 146 to pass through the furring strip and a hole 143, and a projecting central portion 147. After the attachment means is placed in the manner shown at 144a, the central portion 147 thereof may be driven in by hammer blows as shown at 144b, causing the inner ends 148 of the legs 146 to expand within the pipe 50 so as to prevent removal of the attachment means from the opening 143. To the furring strips 142 a selected lath means 150 may be secured, and upon this a layer of stucco 151 or plaster 152 may be placed.

Fig. 8 also illustrates the manner in which metal reinforcing 153 may be connected to a horizontal pipe member 155 secured by fittings in the manner hereinbefore described, a body of concrete 156 being cast around the reinforcing 153 and the pipe 155 to form a floor 157 and an edge wall 158 resting on the concrete foundation member 16a.

Although I have herein shown and described my invention in simple and practical form, it is recognized that certain parts or elements thereof are representative of other parts, elements, or mechanisms which may be employed in substantially the same manner to accomplish substantially the same results; therefore, it is to be understood that my invention is not to be limited to the details disclosed herein but is to be accorded the full scope of the following claims.

I claim as my invention:

1. A structural frame of the character described,

including: a main structural member consisting of a pipe; a secondary structural member; and a fitting for securing said secondary member to an intermediate portion of said pipe without necessity of dividing said pipe, comprising a split body having means for clamping it around said pipe, there being a plurality of substantially circumferential grooves disposed in parallel planes in the surface of said pipe engaged by complementary ribs on the inner face of said body.

2. A structural member for a structural frame of the character described, comprising a bar adapted to have its ends secured in a structure, an intermediate portion of said bar having a plurality of evenly spaced, circumferential grooves disposed in parallel planes in the external face thereof for engagement by a fitting having complementary ribs to cooperate with said grooves.

3. A structural frame of the character described, including: a pair of main pipes; a secondary pipe extending between intermediate portions of said main pipes; and fittings for securing said secondary pipe to said intermediate portions of said main pipes, said fittings each having a body and means for clamping said body against the intermediate portions of the main pipes, said body having projecting circumferential rib means disposed in parallel planes on the inner face thereof, and said intermediate portions of said main pipes having complementary groove means for engagement by said rib means of said body.

4. A structural frame of the character described, including: a pair of main pipes; a secondary pipe extending between intermediate portions of said main pipes; and fittings for securing said secondary pipe to said intermediate portions of said main pipes, one of said fittings having a body and means for clamping said body against the intermediate portions of the main pipes, said intermediate portions of said main pipes having circumferential grooves therein disposed in parallel planes and said fitting having complementary ribs on the inner face thereof to engage said grooves in said intermediate portions of said main pipes.

5. A fitting for structural frame members adapted to be secured to an intermediate portion of a bar-like structural member, including: a body having a wall with a depression therein, adapted to engage said member, there being a plurality of laterally directed, substantially parallel projecting ribs on said wall for engagement with complementary grooves provided by said member; and means for clamping said wall against said member.

6. A fitting for structural frame members adapted for attachment to a bar-like member in a structure, including: a pair of semi-cylindrical walls adapted to fit around said member, said

walls being hinged together so as to be swung between open and closed positions, the inner faces of said walls having laterally extending ribs for engagement with circumferential grooves disposed in parallel planes provided by said member; and means for clamping said walls together in closed position on said member.

7. A structural frame of the character described, including: a main structural member consisting of a pipe; a secondary structural member; and a fitting for securing the said secondary member to an intermediate portion of said pipe without necessity of dividing said pipe, comprising a body and means passing around said pipe to hold said body thereagainst, there being a plurality of parallel circumferentially extending grooves disposed in the surface of said intermediate portion of said pipe and a plurality of complementary ribs on said body engaging said grooves of said pipe.

8. A structural member for a structural frame of the character described, comprising a bar adapted to have its ends secured in the structure, an intermediate portion of said bar having parallel circumferentially extending grooves disposed in the external face thereof for engagement by a fitting having complementary ribs to cooperate with said grooved means.

9. A structural frame of the character described, including: a main structural member consisting of a pipe; a secondary structural member; and a fitting for securing said secondary member to an intermediate portion of said pipe without necessity of dividing said pipe, comprising a body and means movable relative to said body and passing around said pipe to hold said body thereagainst, there being shoulders disposed in parallel lateral planes on the exterior of the pipe in said intermediate portion of said pipe to form groove means therebetween and a plurality of laterally extending complementary ribs on said body engaging said groove means of said pipe.

10. A structural frame of the character described, comprising: a main structural member consisting of a pipe, the main portion of said pipe having a smooth external surface, and said pipe having a grooved section consisting of a plurality of laterally directed, evenly spaced grooves separated by ribs; a secondary structural member; and a fitting for securing said secondary structural member to said grooved section of said pipe, said fitting comprising a body having a curved internal wall equipped with ribs and grooves for interengagement with said ribs and grooves of said pipe, and means extending around said pipe and clamping said body against said grooved section.

FREDERICK H. RUPPEL.
